H. G. CRESS

EDUCATIONAL DEVICE

Filed Sept. 28, 1922

INVENTOR
Horatio G. Tress,
BY Harry Macklin,
ATTYS.

UNITED STATES PATENT OFFICE.

HORATIO G. CRESS, OF TROY, OHIO.

EDUCATIONAL DEVICE.

Application filed September 29, 1922. Serial No. 591,066.

To all whom it may concern:

Be it known that I, HORATIO G. CRESS, a citizen of the United States, residing at Troy, in the county of Miami and State of Ohio, have invented a certain new and useful Improvement in an Educational Device, of which the following is a full, clear, and exact description, reference being had to the accompanying drawings.

10 This invention relates to improvements in educational devices, particularly in devices having slots in which buttons having suitable characters or letters thereon may be moved from one slot to another for purposes of assisting children in learning to spell.

Usually devices of this character embody a storage slot and a branch slot leading therefrom, whereby suitably framed buttons may be moved from the storage slot to the branch slot and vice versa. Usually the storage slot extends around the periphery of the device, and is defined by flanges which form a guideway for the buttons. I have found that with this form of construction the flanges may be easily bent, thus rendering it difficult to slide the buttons from one slot to the other.

Accordingly, one of the objects of my invention is the provision of means for reinforcing the edges of such educational devices to protect the flanges or guideways in which the buttons are moved. In addition, my invention includes a construction which may be readily formed of stampings whereby the cost of manufacture is reduced to a minimum.

In carrying out the above objects, I employ a pair of oppositely disposed plates which are shaped to provide a guideway for the buttons, and I extend these plates beyond the normal storage slot and construct a bead by extending the edge of one plate around the edge of the other. Moreover I provide a bead having approximately an elliptical cross section with the major axis thereof longer than the depth of the guide whereby the device may be supported upon the peripheral bead.

The preferred means for carrying out my invention is set forth in the following description which pertains to the accompanying drawings and the essential features are set forth in the claims.

In the drawings, Fig. 1 is a top view of an educational device embodying features of my invention; Fig. 2 is a section on the

line 2—2 in Fig. 1; Fig. 3 is a section through part of the device on an enlarged scale showing more particularly the bead construction on the periphery of the device.

60

My invention is shown in connection with an educational device having a storage slot 10 and a branch slot 11 in which buttons indicated generally at 12 may be moved. The buttons comprise heads 13, 14 which are connected by necks 15; the necks being of such size as to permit free movement of the buttons from one slot to another.

65

My invention in the preferred form embodies a base plate 20 having a channel 21 formed therein to provide a storage slot 10 and another channel 22 leading therefrom forming a branch slot as shown in Figs. 2 and 3. Outside the channel 21, the base plate extends in the same plane as the central portion and is then curved upwardly as at 24 and then in a reverse direction as at 25 and 26 to form part of a hollow bead.

70

Cooperating with this base plate, I provide a peripheral plate, a portion of which, as at 27, engages the flat portion 23 and is rigidly secured, as by welding, thereto. The inner end of this plate is shaped, as at 28, to provide a flange constituting part of a guideway for the buttons 12. The outer end of the plate is curved as at 29, to extend around the bead portions of the base plate, as shown particularly in Fig. 3. The space enclosed by the bead is substantially elliptical in cross section with the major axis thereof extending at right angles to the plane of the plate 20. Moreover, the major axis of the bead is greater than the depth of the storage slot 10 and branch slot 11, whereby the top and bottom portions of the bead lie outside of planes passing through the portions of the plate which form the channel. In this way, the device is supported by the bead when placed upon a table.

75

Within the space defined by the flange 28, I have shown the rest of the facings as face plates 30 and 31 which are attached, as by welding, to the base plate. These plates are shaped to provide flanges 32 and 33 respectively which lie in the same plane as the flange 28 and serve as guideways for the buttons 12. The base and face plates then are attached on a plane passing approximately through the mid-portion of the device and the flanges formed thereby are inside of planes passing through the top and bottom of the bead.

110

A device made according to my invention provides a rugged construction which is capable of withstanding hard usage without distorting the flanged guideways, and thus preventing the buttons from being readily moved from one slot to another. In addition, the formation of channels by shaping both the base and face plates, provides in effect a double corrugation which materially aids in strengthening the plates.

I claim:—

1. A device of the character described, comprising a supporting plate having a facing plate attached thereto and cooperating therewith to provide channels and a hollow bead formed in part by the marginal portion of one of the plates, said bead extending around the device and outside said channels.

2. In a device of the class described, the combination with a supporting plate, of a facing plate attached thereto to provide channels, buttons movable within the channels, and a hollow bead formed by both of said plates and extending around the marginal edges of the plates.

3. In a device of the class described, the combination with a base plate having an endless channel formed therein, of a facing plate attached thereto and having a flange cooperating with the channel, buttons movable within the channel and guided on the flange, and a hollow bead formed in part by the marginal portion of one of said plates and extending above and below the plates of the channel and flange.

4. In a device of the class described, the combination with a base plate having a channel therein and intermediate the edges thereof, a facing plate attached to the base plate and having a flange cooperating with said channel portion, a second facing plate spaced from the first mentioned facing plate and having a flange, said flanges being spaced apart to provide a slot, buttons each having a pair of opposed heads connected by a neck, the necks of said buttons being slideable between said flanges, and a hollow rim formed by the base plate and one of said facing plates.

5. In a device of the class described, the combination with a base plate, of a face plate attached thereto, each of said plates having raised portions which cooperate to provide a slot, buttons each having a pair of opposed heads connected by a neck, the necks of said buttons being slideable within said slot and each of said plates having the marginal portions thereof shaped to form part of a hollow bead.

6. In a device of the class described, the combination with a base plate having an endless channel therein to provide a storage slot and having another channel opening therefrom to provide a branch slot, facing plates having raised flange portions cooperating with said channels to provide a guideway, buttons each having a pair of opposed heads connected by a neck which extends through the opening intermediate said flanges, the base plate and one of the facing plates extending outwardly and in abutting engagement from the storage channel, and said last mentioned plates being curved outwardly and then inwardly upon each other to provide a hollow bead.

7. In a device of the class described, the combination with a base plate, of a face plate cooperating therewith to provide channels, and buttons movable within the channels, said plates having the marginal edges thereof folded over each other to provide a hollow reinforcing bead of elliptical cross section, the major axis of said bead lying in a plane at right angles to a plane passing through one of said plates.

8. In a device of the class described, the combination with a base plate and a face plate formed to provide a guideway, and buttons each having a pair of opposed heads connected by a neck which occupies said guideway, said plates extending outwardly in abutting engagement and being then curved outwardly and then inwardly one upon the other to provide a hollow bead.

In testimony whereof, I hereunto affix my signature.

HORATIO G. CRESS.
